UNITED STATES PATENT OFFICE.

ERNEST ALFRED LAMBERT, OF HADLEIGH, AND STANLEY GEORGE WENMAN-ADIE, OF NORTHIAM, ENGLAND.

INTERNAL-COMBUSTION ENGINE.

1,323,873.

Specification of Letters Patent.

Patented Dec. 2, 1919.

Application filed June 25, 1919. Serial No. 306,588.

To all whom it may concern:

Be it known that we, ERNEST ALFRED LAMBERT and STANLEY GEORGE WENMAN-ADIE, subjects of the King of Great Britain, 5 residing at Hadleigh, Suffolk, England, and Northiam, Sussex, England, respectively, have invented new and useful Improvements in or Relating to Internal-Combustion Engines, of which the following is a specification.

This invention is concerned with the starting and reversal of internal combustion engines and the like fluid pressure engines and has for its object to provide improved 15 means for controlling the distribution of compressed air or other working fluid to cylinders arranged for starting and reversing the crank shaft.

The invention consists of a distributing 20 valve comprising a stationary outer member having supply and delivery connections for the working fluid, a rotatable inner member provided with a port to which the working fluid is supplied from the supply connection on the outer member, and an angularly adjustable intermediate member capable of a limited axial movement adapted to control the passage of the working fluid from a distributor port in the inner member 25 to the delivery connections of the outer member.

There may also be provided in combination with the intermediate member means for automatically controlling the supply of 30 the working fluid to the supply connection in the outer member.

In the accompanying drawings,

Figure 1 is a vertical sectional view of the improved distributing valve for a four cylinder engine.

Fig. 2 is an end elevation of the same with the air cylinder removed.

Figs. 3 and 4 are transverse sectional views taken on the lines 3—3 and 4—4 respectively, 45 of Fig. 1.

Like parts are designated by similar reference characters throughout the drawings.

Referring to the drawings,

2 represents the stationary outer member having a supply connection 2^a and four delivery connections 2^b for the working fluid.

An attachment plate 2^c is provided on the outer member by which it is firmly secured to some fixed part.

55 3 indicates the inner member which has a

port 3^a to which air is supplied from the supply connection 2^a in the outer member 2.

4 is the adjustable intermediate member which controls the passage of the working fluid from the distributor port 3^c in the inner member to the delivery connections 2^b in the outer member.

5 is a cylinder having a plunger 5^a in operative connection with the intermediate member 4 and provided with supply and delivery ports 5^b, 5^c for the working fluid. As shown, said cylinder is carried by a bracket 5^d attached to the base of the outer member.

6 is a rotating shaft to which the inner member 3 is loosely keyed, said shaft being 70 rotated in unison with the crank shaft of the engine or air motor so that the opening and closing of the various ports at any instant synchronize with the cycle of operations in the different cylinders to which the 75 working fluid is supplied.

The various delivery ports 2^b may either be coupled up direct to the cylinders of the internal combustion engine or to the cylinders of an auxiliary starting and reversing engine or motor the shaft of which would be adapted for operative connection with the crank shaft of the main engine.

In the concrete example shown in the drawings, the three members 2, 3 and 4 of 85 the valve are arranged concentrically about the shaft 6 and have suitably machined surfaces for engaging each other in a fluid tight manner.

The inner member 3 is of conical form and capable of a small amount of axial movement on the shaft 6 to which it is keyed, said movement being limited in the one direction by a screw 7 and by the shoulder 8 on the shaft 6 in the opposite direction. 90 This small amount of axial play is provided to allow the inner member to be normally held in close contact with the correspondingly coned inside surface of the intermediate member by means of small compression 95 springs 9 arranged in recesses 10 in the inner member and bearing against the shoulder 8 on the shaft. By means of this arrangement the springs 9 are able to take up 100 any wear between the inner and intermediate members.

Similarly the exterior of the intermediate member is made conical and fits within the correspondingly shaped interior of the outer member.

110

For the purpose of retarding or advancing the admission of the working fluid the intermediate member is adapted to have a limited rotary movement between the inner and outer members, said movement being imparted thereto by suitable mechanical means, such as a control lever and connections, a forked arm 11 being provided on the intermediate member for this purpose.

10 The working fluid may if desired be conducted direct from the source of supply to the outer member. The pressure of supply may however be conveniently utilized to maintain the intermediate member in close 15 working contact with the inner and outer members and for this purpose a cylinder 5 is interposed between the supply pipe 12 and the outer member. This cylinder is fitted with a plunger 5^a which is connected to 20 the intermediate member by a nut 13 and screw shank 14 and takes the full pressure of supply.

Where it is desired that the supply of fluid to the outer member shall be cut off during 25 the period when the intermediate member is moving from one position to another, the said intermediate member may be adapted to have a small amount of axial play relatively to the inner and outer members so that 30 when moved outwardly the said member forces the plunger 5^a forward in the cylinder until its inner end closes the outlet port 5^c therein thus shutting off the supply of fluid for the time being to the supply connection 35 2^a of the outer member. In order that the aforesaid axial movement of the intermediate member shall only take place and have the effect of shutting off the air supply as above explained at a predetermined point 40 or points in the angular adjustment of the said intermediate member, the front of the fixed outer member 2 is provided with cam surfaces 15 upon which rollers 16 carried by the intermediate member ride as the latter is 45 rotated from one position to another.

Air vents 17 are provided in the closed end of the intermediate member to allow for the free axial movement of the same.

The fluid supply from the cylinder 5 is 50 conducted by the supply pipe 12 to the supply port 2^a in the outer member 2 whence it passes through a port 4^a in the intermediate member to an annular groove 3^b see Fig. 4, in the inner member. The port 2^a in the outer member is of sufficient length to maintain a free passage for the air supply 55 through the port 4^a in the intermediate member to the groove 3^b of the inner member irrespective of the change of angular position 60 of the said intermediate member.

Formed in the inner member is a distributor port 3^c of segmental shape, see Fig. 3, between which and the aforesaid annular groove 3^b there is a passage 3^d for admitting 65 fluid from the latter to said port.

The delivery ports 2^b in the outer member are connected by suitable pipes with the engine cylinders or with the starting and reversing cylinders as the case may be and formed in the intermediate member are two 70 sets of ports 4^b in different planes which correspond with the said delivery ports 2^b and control admission of fluid to said ports from the distributor port 3^c in the inner member.

By a rotary adjustment of the intermediate member the position of these controlling ports in relation to the delivery ports 2^a is changed and the admission of the working fluid is advanced or retarded as required, the fluid passing from the distributing port in 80 the inner rotating member to the delivery ports 2^a in succession whence it is conducted to the cylinders in the proper sequence. The angular or circumferential length of the distributor port 3^c governs the period of admission of the fluid to each cylinder. 85

What we claim and desire to secure by Letters Patent of the United States, is—

1. A starting and reversing valve for fluid pressure engines comprising a stationary 90 outer member having fluid supply and delivery ports, a rotatable inner member having a port in communication with the supply port in the outer member, an angularly adjustable intermediate member adapted to 95 control the passage of the working fluid between the inner and outer members, and means for imparting a limited axial movement to said intermediate member during its angular adjustment for the purposes of 100 regulating the supply of fluid to the outer member.

2. A starting and reversing valve for fluid pressure engines comprising a stationary outer member having supply and delivery 105 ports for the working fluid, an inner member having a port in communication with the supply port in the outer member, means for rotating said inner member in unison with the cycle of operations of the engine, an angularly adjustable intermediate member having ports adapted to establish communication between the ports in the inner and outer members, cam surfaces on said outer member and rollers on said intermediate 115 member adapted to ride on said cam surfaces so as to impart axial movement to the intermediate member during its angular adjustment.

3. A starting and reversing valve for fluid pressure engines comprising a stationary outer member having ports for the supply and delivery of the working fluid, a rotatable inner member having a port in communication with the supply port in the outer member, an intermediate member capable of a limited axial movement relatively to the inner and outer members and provided with ports to establish communication between the ports in the said inner and outer members 130

and means operated by the axial movement of said intermediate member to control the supply of fluid to said outer member.

4. A starting and reversing valve for fluid pressure engines comprising a stationary outer member having supply and delivery ports for the working fluid, a conical inner member having a distributor port in constant communication with the supply port in the outer member, a shaft for rotating said inner member in unison with the cycle of operations of the engine, an angularly adjustable intermediate member having a hollow conical interior for the inner member and provided with ports adapted to establish communication on the one hand between the supply port in the outer member and the distributor port in the inner member and on the other hand between the said distributor port and the delivery ports in the outer member, means for imparting a limited axial movement to said intermediate member during its angular adjustment, a cylinder having inlet and outlet ports communicating respectively with the source of fluid supply and the supply port of the outer member, and a plunger attached to said intermediate member and adapted to be moved in said cylinder by the axial movement of the said intermediate member.

5. A starting and reversing valve for fluid pressure engines comprising a stationary outer member having supply and delivery ports for the working fluid, a conical inner member having a distributor port in constant communication with the supply port in the outer member, a shaft for rotating said inner member in unison with the cycle of operations of the engine, an angularly adjustable intermediate member having a hollow conical interior for the inner member and having ports adapted to establish communication on the one hand between the supply port in the outer member and the distributor port in the inner member and on the other hand between the said distributor port and the delivery ports in the outer member, cam surfaces on the fixed outer member, rollers carried by said intermediate member and adapted to ride on said cam surfaces so as to impart a limited axial movement to said intermediate member during its angular adjustment, and means operatively connected with said intermediate member for controlling the supply of fluid to the outer member.

6. A starting and reversing valve for fluid pressure engines comprising a stationary

outer member having a hollow conical interior and provided with supply and delivery ports, a conical intermediate member angularly adjustable within said outer member and having an oppositely conical interior, ports in said intermediate member communicating with the supply and delivery ports in the outer member, a conical inner member adapted to rotate within said intermediate member in unison with the cycle of operations of the engine and having a distributor port in communication with the ports in the intermediate member, means for imparting a limited axial movement to said intermediate member relatively to said inner and outer members, a cylinder provided with inlet and outlet ports communicating respectively with the source of fluid supply and with the supply port in the outer member, a plunger working in said cylinder and operatively connected with said intermediate member.

7. A starting and reversing valve for fluid pressure engines comprising a stationary outer member having supply and delivery ports for the working fluid, an angularly adjustable intermediate member having ports corresponding with the supply and delivery ports in the outer member, means for imparting a limited axial movement to said intermediate member during its angular adjustment, an inner member having an annular groove opposite the supply port in the intermediate member and a distributor port opening into said groove and adapted to establish successive communication with the delivery ports in said intermediate member, a shaft for rotating said inner member in unison with the cycle of operations of the engine, a cylinder provided with inlet and outlet ports communicating respectively with the source of fluid supply and with the supply port in the outer member, and a plunger working in said cylinder and operatively connected with said intermediate member.

In testimony whereof we have signed our names to this specification in the presence of two subscribing witnesses.
